[57] **CLAIM**

The ornamental design for a transparent protective cover for a bank machine, as shown and described.

DESCRIPTION

FIG. 1 is a rear and bottom-right perspective view of a transparent protective cover for a bank machine showing my new design;

FIG. 2 is a front and top-left perspective view; and
FIG. 3 is a front and top-right perspective view.

The broken lines showing of FIG. 3 is for environmental purposes only and forms no part of the claimed design.

FIG.1

FIG.2

FIG. 3
